UNITED STATES PATENT OFFICE.

CARL LIKE, OF SAN FRANCISCO, CALIFORNIA.

DIRECTION INDICATOR.

Application filed May 21, 1924. Serial No. 714,833.

To all whom it may concern:

Be it known that I, CARL LIKE, a citizen of the United States, residing at San Francisco, in the county of San Francisco and 5 State of California, have invented new and useful Improvements in Direction Indicators, of which the following is a specification.

This invention relates to improvements 10 in direction indicators in which an advertising sign or plate has associated therewith a novel means for indicating the direction of certain designated points.

An object of this invention is to provide 15 a direction indicator of novel design and construction, which may be used both for advertising purposes and as a means to indicate the direction and distances of certain designated places.

Another object of this invention is to provide 20 a direction indicator which may be used to designate the direction and distance of a plurality of places, as well as to display some advertisement.

In the drawing, forming a part of this 25 application:

Fig. 1 is a front view of the direction indicator, showing the manner in which the same is formed;

Fig. 2 is a rear view of the same; and 30

Fig. 3 is a cross section taken on the line 3-3 of Fig. 2, showing the means used for attaching the plate to the upright post.

Referring to the drawings, 1 represents 35 an upright post, provided at the top with a suitable recess into which a projection 2, of the square shaped plate 3, is inserted. The plate is secured to the post by means of bolts 4, which extend through the projection 2 and the post 1.

The plate 3, may be constructed from 40 any suitable material, such as metal or wood, and is provided at three of its corners with arrow shaped members 5. The central portion of the plate is inscribed with suitable lettering or designs 6, which may assume 45 the form of advertising matter, while the

arrow shaped members are provided with lettering and figures 7, suitable for indicating the distances of certain places. The 50 advertising matter 6 of the sign may be colored in some particular shade, and the arrow member 5 pointing in the direction where the place or thing advertised is situated, may be colored in the same shade. 55 The main highway or road may be designated by one of the arrows having thereon some particular color, while the other arrows may be colored in some other shade or hue. Thus the signs or direction indicators, may, if there be a number displayed along a highway, be each provided with an arrow of some particular color used to designate the main highway, while another arrow may be colored in the same hue as the 60 advertisement and used to designate the town or city where the thing advertised is situated.

It is apparent that the invention herein disclosed may assume other forms or shapes 70 and may be constructed in a manner somewhat different than the form shown on the drawings, so for that reason I do not desire to be limited to the exact disclosure herein made, it being sufficient to state that 75 the claims hereunto appended will be construed as a definition of the limits of my invention.

What I desire to claim is:

1. A direction indicator comprising an upright post, a square shaped plate secured to the post at one of its corners, and a plurality of varied colored arrow shaped members attached to the other corners of the plate. 80

2. A direction indicator comprising an upright post, a square shaped plate having three corners thereof provided with varied colored arrow shaped members and the body portion thereof provided with a particular 85 color, and a means for attaching the plate to the post. 90

CARL LIKE.
